UNITED STATES PATENT OFFICE

JOHN A. JOHNSTON, OF PROVO, UTAH

POULTRY FOUNTAIN

Application filed August 11, 1927. Serial No. 212,261.

The present disclosure of the invention relates to a drinking fountain for poultry, said fountain embodying a water container and a novel form of guard therefor which will prevent the chicks or chickens, as the case may be, from walking into the container, while permitting them to insert their heads when drinking, it being understood that the guard may have its guard members spaced different distances apart, according to whether the device is to be used for chicks, grown poultry, etc.

It is the object of the invention to provide a drinking fountain or perhaps a container for feed, equipped with a novel form of guard which is held in place by engagement of resilient guard members with an outstanding rim on the water or other container, said guard being readily removable simply by springing said guard members out of engagement with the container rim, and being re-engageable with the container with equal ease.

With the foregoing in view, the invention resides in the novel subject matter herein-after described and claimed, the description being supplemented by the accompanying drawings.

Fig. 1 is a vertical sectional view of a poultry fountain constructed in accordance with my invention.

Fig. 2 is a horizontal sectional view on line 2—2 of Fig. 1.

In the drawings above briefly described, the numeral 3 designates a container for drinking water, the upper end of said container being provided with an outstanding rim 4 of any desired configuration. Connected with the lower end of the container 3, is a pipe line 5 provided with an appropriate valve 6 and preferably having a union 7. Near the upper end of the container is an overflow spout 8 and it will be seen that by opening the valve 6, fresh water is discharged into the container and the stale water from the latter will overflow through the outlet spout 8, so that it is an easy matter to substitute fresh for stale and perhaps dirty water.

To prevent the poultry from stepping into

the container 3, a guard 9 is provided, said guard embodying a plurality of resilient guard members 10 having U-shaped seats 11 near their lower ends, normally engaged with the edge of the rim 4. Below the seats 11, the guard members preferably slant outwardly as at 12 to facilitate engagement of the guard with the rim 4, simply by downward forcing of said slanted ends against the upper side of the rim. Moreover, the construction of the seats 11 permits removal of the guard simply by pulling it upwardly.

In the preferred form of construction, the guard members 10 are formed by vertical lower portions of a plurality of resilient wires, said portions being spaced apart along a circular line. The upper portions 13 of the lengths of wire, converge to a common point and are preferably welded together as denoted at 14. A cover 15, preferably formed of sheet metal, surrounds all of these upwardly converging wire portions to hold them against spreading, and said cover is preferably secured to the wires by soldering at the points 16.

Attention is invited to the fact that at these points 16, shoulders are provided between the inwardly curved upper ends of the wire portions 10 and the inwardly inclined upper portions 13 of the wires. These shoulders effectively support the cover 15 in its proper relation with the wires while the latter are being soldered to said cover and hence these features of construction are of important manufacturing advantage.

It will be seen from the foregoing that the invention is exceptionally simple and inexpensive, yet that it will be efficient and very desirable for the intended purposes. As excellent results are obtainable from the details disclosed, they are preferably followed. However, within the scope of the invention as claimed, variations may be made.

I claim:

1. A container guard having a plurality of vertical resilient arms between which the poultry may pass only their heads, said arms being relatively fixed at their upper ends but free to spring radially at their lower ends, said arms being formed with U-shaped out-

wardly bowed container-engaging seats near their lower ends to receive the rim of a container and support said arms with their fixed upper ends spaced above said container, said 5 lower ends being provided with outwardly declined terminals directly below said seats, said terminals serving to effect outward movement of the arms upon downward forcing of the guard upon a container rim, the 10 lower portions of said seats being declined inwardly to effect outward movement of the arms upon upward pulling of the guard from the container; said arms and their seats constituting the sole attaching means for the 15 guard, the resiliency of said arms being the sole means for holding their seats in engagement with the container rim.

2. A container guard comprising a plurality of wires having vertically elongated 20 portions spaced apart along an annular line sufficiently to permit poultry to pass their heads only between them said vertical portions being bent near their lower ends to provide U-shaped outwardly bowed container- 25 engaging seats, the lower extremities of said vertical portions being declined outwardly immediately below said seats to outwardly force said vertical wire portions upon downward forcing of the guard upon the container rim, the lower portions of said seats being inwardly declined to permit removal of the guard from the container rim by upward pulling upon said guard, said vertical wire portions being curved inwardly at their upper 35 ends at points spaced upwardly from said seats sufficiently to permit the poultry to insert their heads below said points, the upper portions of said wires being inclined from said inwardly curved ends of said vertical 40 portions to a common central point at which they are secured together, said inclined upper portions of said wires joining said inwardly curved upper ends of said vertical portions at an angle to provide upwardly facing shoulders, and a conical cover over the full lengths of said upper inclined wire portions, said cover resting at its lower edge upon and being secured against said shoulders.

In testimony whereof I have hereunto 50 affixed my signature.

JOHN A. JOHNSTON.
